COMBINED SHOE TREES AND BOX THEREFOR OR SIMILAR ARTICLE

Cynthia Carlin, New York, N. Y.

Application May 28, 1953, Serial No. 25,235

Term of patent 14 years

(Cl. D58—12.6)

To all whom it may concern:

Be it known that I, Cynthia Carlin, a citizen of the United States of America, residing in New York city, county of New York, and State of New York, have invented a new, original, and ornamental Design for Combined Shoe Trees and Box Therefor or Similar Article, of which the following is a specification, reference being had to the accompanying drawing, forming part thereof.

Fig. 1 is a side perspective view of combined shoe trees and box therefor or similar article, showing my new design.

Fig. 2 is a bottom perspective view of the cover portion of the box illustrating the shoe trees which are attached to the cover portion.

Fig. 3 is a side elevational view of the shoe tree box.

I claim:

The ornamental design for combined shoe trees and box therefor or similar article, substantially as shown.
